CONTAINER

Calvin A. Agar, West Orange, N. J.

Application May 11, 1933, Serial No. 670,401

2 Claims. (Cl. 229—27)

While the present invention is not limited to such use, it is particularly intended for convenient carrying of a half-dozen bottles of beer or other beverage.

5 An object of the invention is to provide a container for the above purpose, capable of completely enclosing the bottles in secure non-shifting relation and out of contact with each other, and which will distribute the strains due to the 10 weight of the contents when carried in suspended relation in such manner as to avoid injury to the container, even though the latter be made of relatively weak and inexpensive stock.

Another object is to provide a container of the 15 above type, in the form of a carton, that may be kept in flat condition and that may be conveniently set up for use when required and will yet have substantially the strength of non-collapsible containers, and in which in particular, the 20 strain is transmitted from the carrying handle to the bottom of the container without oblique or other destructive strains on the cover and/or side walls of the container.

Another object is to provide a carton of the 25 above type, involving longitudinal and transverse partitions forming compartments for the individual bottles, and affording struts for reinforcing the outside of the container and for sustaining substantially the entire strain when the package 30 is carried in suspended relation.

Another object is to provide a carton of the above type, made from a single blank maintained in set-up relation solely by interfolding of various parts thereof, to form the entire structure 35 including the longitudinal and transverse partition members, cover members and carrying handle.

Another object is to provide a blank roughly 40 rectangular in shape that may be prepared with but little waste of stock, and capable of being readily set up by interfolding to produce a carton structure of the above character.

Other objects will be in part obvious and in part pointed out hereinafter.

45 In the accompanying drawings, in which is shown one of various possible embodiments of the several features of the invention,

Fig. 1 is a perspective view of the portable container, in closed condition,

50 Fig. 2 is a transverse sectional view taken on the line 2—2 of Fig. 1,

Fig. 3 is a view in longitudinal cross-section, lengthwise of the carton,

55 Fig. 4 is a view in transverse cross-section taken on the line 4—4 of Fig. 3,

Fig. 5 is a plan view of the developed blank,

Fig. 6 is a perspective view showing the blank in the process of being folded to produce the carton, and

Fig. 7 is a perspective view showing the carton in a more advanced state of set-up.

Referring now to Figs. 1 to 4 of the drawings, the container roughly comprises a rectangular bottom 10, side walls 12 and 14 and end walls 11 and 13. A longitudinal partition wall 15, 16 extends midway between the side walls 12 and 14, through the entire length and height of the container, and transverse partition members 17, 18, 19 and 20 subdivide the container illustratively into six compartments, for the individual bottles. The container has cover elements 21 and 22, each of a width substantially half the thickness of the container from between which protrudes upwardly a handle structure 23, 24 unitary with the median longitudinal partition 15, 16.

The construction thus far described, substantially regardless how built, provides the advantage of transmitting the strain due to the weight of the contents resting on the bottom, substantially solely through the median partition 15, 16 to the carrying handle 23, 24. The partition being of uniform strength throughout its height below the handle, there is no region of weakening where it is apt to break or tear, and oblique or skew strains on the container wall are avoided, so that the parts may be of relatively weaker or lighter stock than constructions in which the strain is not as directly transmitted.

The construction shown in Figs. 1 to 4 is preferably made of a blank shown developed in Fig. 5, and which will now be described.

The blank, preferably of a thin grade of stiff, double-faced corrugated paper board is roughly rectangular in form, and accordingly is made with but little waste of stock. The blank is longitudinally and transversely scored and longitudinally slit as shown and more fully set forth below. The blank includes four panels 11, 12, 13 and 14 joined at longitudinal score lines *s* in a lateral sequence with a tucking tongue 25 at the lateral edge of the blank. The panels 12 and 14 of greater width determine the side walls of the carton and the narrower panels 11 and 13 the end walls thereof. The blank is longitudinally slit both at its upper and lower edges as at *t* in alignment with the score lines *s* between the respective panels. The flaps thus formed, which extend from that edge of the wall panel at the bottom of the set-up carton, are longer than said panels and said flaps are scored as at

u parallel to the score line *v* between the panels and the flaps, the area between said scores *u* and *v* being of a width substantially half the thickness of the finished carton and determining the bottom panels 10 and 10' of the carton. The slits *w* divide the flaps associated with the narrower panels 11 and 13 into identical laterally aligned transverse partition flaps 17 and 18, and the flaps 20 and 19 respectively. The foot 26 of each of the transverse partition flaps serves as the spacer from the corresponding end wall.

The flaps at the ends of the panels at the top of the set-up carton serve as the cover. The flaps 21 and 22 are scored at *y* to form tucking flaps 30, the distances between the score line *x* determining the upper edge of the panel in the set-up carton, and the score *y* being each substantially half the thickness of the set-up carton. The corresponding flaps of the narrower panels 11 and 13 are longitudinally slit at *z* in alignment with slits *w*, each to form two segments 31 and 32.

The narrower flap portions 17, 18, 19 and 20 beyond score line *u* and associated with panels 11 and 13, are preferably of a length equal to 25 the height of said panels. The wider flap portions 15 and 16 associated with panels 12 and 14 are of greater length to determine handle flaps 23 and 24 with hand holes 34 therein, said handle members being connected at corresponding score 30 lines *r* aligned with the extremities of the flaps 17, 18, 19 and 20.

The carton shown in Figs. 1 to 4 is set up, as required, from the blank of Fig. 5 just described, by an interfolding operation now to be set forth 35 and illustrated in Figs. 6 and 7. In the set-up container, the bottom-forming narrower panels 10 and 10' of the blank are brought into abutment at their limiting score lines *u*, and the partition-forming panels 15 and 16 with their 40 handles 23 and 24 are brought into face to face engagement. The longitudinal slit *w* between flaps 17 and 18 is caused to straddle the superposed longitudinal partition members 15 and 16 so as to dispose the flaps 17 and 18 as transverse 45 partitions extending on opposite sides of the longitudinal partition. The foot 26 of each of said transverse partition flaps is superposed over the corresponding bottom segments 10, 10', and determines the distance of said transverse partitions from the end wall. Similarly, the slit *w* between transverse partition flaps 19 and 20 is caused to straddle the superposed longitudinal partition members 15 and 16, and the foot 26 of each of said members determines the distance 50 of said transverse partitions from the corresponding end wall of the carton. In the process of interfolding the partition members set forth, the wall panels 11, 12, 13 and 14 are folded into a rectangular enclosing structure and the tucking tongue 25 is then tucked into place.

The bottles or other articles may now be inserted into their individual compartments as shown in Fig. 2, and thereupon the respective flaps 31 and 32 may be folded in from the end walls to extend at opposite sides of the protruding handle members 23 and 24, and finally the cover flaps 21 and 22 may be folded down with their tongues 30 tucked in as first shown in Fig. 4 into face to face contact with the longitudinal 65 partition members 16 and 15 respectively. The distance between the flaps 31 and 32 must be four times the thickness of the stock, since there is accommodated therebetween not only the double thickness of the longitudinal partition 70 members 15, 16, but the double thickness of the two tuck-

ing tongues 30. For this reason, the slit *z* defining said tongues is of correspondingly greater width, as shown, than the remaining slits.

No auxiliary tools or appliances of any kind whatsoever are required to set up the carton, as required by the beer salesman, from the plain flat blank. No staples, glue strip or other auxiliary holding means need be used.

When the complete carton is carried from the handle members 23, 24, the weight of the contents sustained on the bottom is transmitted substantially directly through the width and height of the vertical longitudinal partition structure 15, 16. There is no weakened region in this carrying partition where rupture, under the weight 10 of the package contents, would be apt to occur, since the partition is of uniform area at each horizontal cross-section below the hand hole 34, and is not weakened at any locality by tongues, slits or the like. The transverse carrying partition 15 is connected at its base directly to the bottom 10, 10' at the median line of the latter, and is free from any direct mechanical connection to the lateral walls or top of the container. Thus, 15 there is assurance that the stress is transmitted vertically and no destructive oblique or skew strains on the walls of the carton or on its cover are incurred.

In the closed package, the transverse partitions 17, 18, 19 and 20 maintain the longitudinal 30 partition structure 15, 16 from hinging movement, and the bottles retain the transverse partitions in correct relation to separate the bottles from contact with each other.

The transverse partition members 17, 18, 19 and 20 35 also serve as struts reacting against the bottom, top, side walls and longitudinal partition to thus resist any tendency for the bottom segments to hinge upwardly under tension transmitted through partition 15, 16. The spacer feet 40 26 also act as struts to resist such hinging movement of the bottom segments, said spacer feet, the cover tabs 31, 32, the cover flaps 21, 22, and the various partition members also operating 45 jointly and severally as reinforcing struts to strengthen the lateral walls of the carton.

While the carton described is particularly convenient for carrying a half dozen bottles of beer or other beverage by the ultimate consumer from the retail store, it will be readily understood that 50 four of these filled cartons may be readily packed, when shipping a case of beer, the two parts 23 and 24 of the handle member in that case being simply folded down to afford a plain rectangular container, convenient for shipping or packing.

Since the cover flaps are readily opened for access to the bottles, the package may be used for returning the empty bottles to the retail store and may be reused indefinitely.

It will thus be seen that there is herein described apparatus in which the several features of this invention are embodied, and which apparatus in its action attains the various objects of the invention and is well suited to meet the 65 requirements of practical use.

As many changes could be made in the above construction, and many apparently widely different embodiments of this invention could be made without departing from the scope thereof, 70 it is intended that all matter contained in the above description or shown in the accompanying drawings shall be interpreted as illustrative and not in a limiting sense.

Having thus described my invention, what I 75

claim as new and desire to secure by Letters Patent of the United States is:—

1. A container comprising joined side and end walls, the side walls each having an integral half-size bottom flap, each having an extension forming an upstanding partition member in face-to-face contact with the other and projecting above the top of the container, and each end wall having slotted flaps integral therewith at the lower end thereof and resting on said bottom flaps, the body portion of each of said slotted flaps being of a length substantially equal to one-third the width of said side walls and each slotted flap having an upwardly extending terminal portion of the full width of said bottom flaps and of the full height of said side walls, and one of said side walls having a flap along one lengthwise edge thereof and folded inwardly along the inner surfaces of the adjacent end wall and resting upon the adjacent one of said slotted flaps, and each of said side walls at its upper end having integral therewith half-size top flaps adapted to rest upon the upper ends of the extensions of said slotted flaps.
2. A container comprising joined side and end walls, the side walls each having an integral half-size bottom flap, each having an extension forming an upstanding partition member in face-to-face contact with the other and projecting above the top of the container, and each end wall having slotted flaps integral therewith at the lower end thereof and resting on said bottom flaps, the body portion of each of said slotted flaps being of a length substantially equal to one-third the width of said side walls and each slotted flap having an upwardly extending terminal portion of the full width of said bottom flaps and of the full height of said side walls, and each of said side walls at its upper end having integral therewith half-size top flaps adapted to rest upon the upper ends of the extensions of said slotted flaps.

CALVIN A. AGAR.
